UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PLURAL LAMP SOCKET.

Application filed April 23, 1919. Serial No. 292,197.

To all whom it may concern:

Be it known that I, REUBEN B. BENJAMIN, a citizen of the United States, residing at Chicago, in the county of Cook and State of Illinois, have invented new and useful Improvements in Plural Lamp Sockets, of which the following is a full, clear, concise, and exact description, reference being had to the accompanying drawing, forming a part of this specification.

My invention relates to improvements in plural lamp sockets, and has for one of its objects the production of a simple, compact, and serviceable lamp socket in which the lamp-receptacle-carrying part may be made in a single piece of molded material having suitable recesses and apertures therein to permit the easy and ready assemblage within the insulating body portion of the various lamp receptacles and conductor members, provision being made for the extending of the conducting members to terminals on the exterior of the body.

For the purpose of disclosing my invention I have illustrated certain embodiments thereof in the accompanying drawings. In these drawings—

Fig. 1 is a front elevation of a twin lamp socket embodying my invention;

Fig. 2 is a side elevation thereof, a portion of the body being broken away to show a part of the interior construction;

Fig. 3 is a sectional view taken on the line 3—3 of Fig. 1;

Fig. 4 is a sectional view taken on the line 4—4 of Fig. 2;

Figs. 5 and 6 are perspective views of the conducting members for the receptacle terminals;

Fig. 7 is a side elevation of a modified form of my invention, a portion of the body being broken away;

Fig. 8 is a sectional view taken on the line 8—8 of Fig. 9;

Fig. 9 is a sectional view taken on the line 9—9 of Fig. 8;

Fig. 10 is a sectional view taken on the line 10—10 of Fig. 8;

Fig. 11 is a bottom plan view of the construction shown in Fig. 7;

Fig. 12 is a perspective view of the switch mechanism.

In the embodiment of the invention illustrated, I provide an insulating body member 1, which body member is preferably of a

general cylindrical shape and has formed at one side thereof a cylindrical extension 2. Formed in the lower end of the body portion 1 is a receptacle recess 3 and a similar recess 4 is formed in the extension 2. The body, comprising the cylindrical portion 1 and its extension 2, is preferably made of molded insulating material and is of such shape and construction that it can be molded in one single piece, thereby avoiding the necessity of assembling a plurality of molded portions to form a body portion, and reducing, therefore, the cost and the use of screws or other assemblage connecting devices. Within the body portion and communicating both with the receptacle recess 4 and the receptacle recess 3 I provide a plurality of longitudinally extending channels 5, 6 and 7. These channels are preferably elongated and at their sides merge into the recess 4 and at their bottoms merge into the recess 3. Each of the two side channels 5 and 7 is of just sufficient width and length to receive a U-shaped conducting member having a base 8 and two angularly disposed legs 9. A threaded shell 10 is disposed within the recess 4. This shell is of the usual construction, having inturned flanges at its bottom, and these inturned flanges are connected, respectively, by screws 11 with the base 8 of each of the U-shaped shell conductor members. A similar threaded shell 12 is arranged within the recess 3 and its bottom portion is connected by means of screws 13 with the bottom legs 9 of the threaded shell conductors. These U-shaped shell conductors are secured in position by means of screws 14, which pass through the body portion from the top and screw into the top leg 9 thereof. These screws 14 also secure in position a threaded shell contact 15. The third U-shaped member is longer than the other two members and is provided with a base 16, a tongue 17 and a second tongue 18. This member is located within the center recess 6 and the base 16 forms the center contact for the threaded shell 10, while the tongue 17 forms the center contact for the shell 12. This center contact member is secured in position by means of an elongated screw 19 which passes through the top of the body member and also through an insulating plug 20, securing the plug 20 in position and forming in connection with a washer 21 on the end of the plug a plug center contact.

In the structure illustrated in Figs. 7 to 12, I have shown a twin plug receptacle of the same type as that illustrated in Figs. 1 to 6, with the addition of a switch for controlling the circuit of one of the receptacles. In this structure, instead of making the center contact 17 and 16 all in one piece, the center contact 17 is made in a separate piece and secured to the base by means of a screw 22 fastening into a nut 23 molded in the body when the body is formed. A spring contact blade 24 is secured in position at the rear of the contact member 16 by the screw 19 and a similar spring contact blade 25 is mounted on the contact 17, these contact blades being disposed so that their free ends are opposite one another. Mounted in a recess 26 in the body is a switch member comprising a bridging contact 27 mounted on a pin 28 extending through the body. An operating handle 29 formed of insulating material is also mounted on this pin and projects beyond the side of the body. This handle is connected with the blade by means of a bar 30 having at one end a pin 31 resting in notches 32 in the end of the switch handle 29 and projecting through an opening in the front end of the U-shaped contact member 27. Interposed between the front end of the U-shaped contact member and a shoulder at the rear of the bar 30 is a coiled spring 33, this construction being such that when the handle 29 is raised past the dead center on the pin 28 the contact 27 will be snapped up, and vice versa. When the contact 27 is snapped down it bridges the spring blades 24 and 25, and thus completes the circuit of the center contact 17. Correspondingly, when the bridging contact 27 is snapped up, the circuit for the center contact 17 is opened and the circuit, therefore, through this receptacle is opened.

It is seen from the above description that I have provided a simple plural plug cluster wherein a one-piece molded body is provided, within which may be mechanically secured and arranged in position the various conductor members of a receptacle of this character.

Having thus described my invention, what I claim as new and desire to secure by Letters Patent, is:—

1. A two-way plug comprising a plug portion and a receptacle sub-assembly, said plug portion comprising shell and center contacts, and insulation for positioning and insulating said contacts with respect to each other, said receptacle sub-assembly comprising a pair of threaded shell contacts, a pair of center contact members, a pair of stampings electrically and mechanically connecting said receptacle shell contacts and located on opposite sides of the plane through the axes of said receptacle shell contacts, a

stamping member lying substantially in said plane for supplying current to said center receptacle contact members, and means for securing said receptacle sub-assembly to said plug portion and for electrically connecting the plug contacts with the receptacle contacts comprising three substantially parallel screw members threaded into said stampings respectively, and lying in a plane perpendicular to the plane through the axes of the receptacle shell contacts. 70

2. A two-way plug comprising a plug portion and a receptacle sub-assembly, said plug portion comprising shell and center contacts, and insulation for positioning and insulating said contacts with respect to each other, said receptacle sub-assembly comprising a pair of threaded shell contacts, a pair of center contact members, a pair of stampings electrically and mechanically connecting said receptacle shell contacts and located on opposite sides of the plane through the axes of said receptacle shell contacts, a stamping member lying substantially in said plane for supplying current to said center receptacle contact members, and means for securing said receptacle sub-assembly to said plug portion and for electrically connecting the plug contacts with the receptacle contacts comprising three substantially parallel screw members threaded into said stampings respectively, and lying in a plane perpendicular to the plane through the axes of the receptacle shell contacts, said receptacle shell contacts having inwardly extending flanges, and said pair of stampings engaging said flanges. 80

3. A two-way plug comprising a plug portion and a receptacle portion, said plug portion comprising shell and center contacts, and insulation for positioning and insulating said contacts with respect to each other, said receptacle portion comprising a pair of threaded shell contacts, a pair of center contact members, metal supporting means electrically and mechanically connected to said electrical shell contacts, and means for securing said metal supporting means in place, and electrically connecting the plug shell contact with the receptacle shell contacts comprising two parallel screw members threaded into said metal supporting means and located on opposite sides of the plane through the axes of said receptacle shell contacts. 90

4. In a device of the character described, the combination with a molded insulating body having a shell receptacle recess in one end and a shell receptacle recess in one side extending at right angles to the end recess, of U-shaped conductor members mounted at the rear of said side recess, screws extending through the top of said body and into one leg of said conductor members, a threaded lamp-receiving shell mounted in 100

100

135

said side recess and secured to the base of said U-shaped members, a second threaded lamp-receiving shell mounted in said end recess and secured to the opposite leg of 5 said U-shaped members, and a center contact for each of said threaded lamp-receiving shells arranged at the bottom thereof and arranged to be electrically connected with a terminal on the top of said body, said holding screws being connected with a terminal on the top of said body. 10

means for securing said threaded shell receptacle contacts to said anchorage means, said anchorage means comprising a sheet metal stamping, and said securing means comprising screws threaded into said stamping, each of said threaded shell receptacle contacts having an inwardly extending flange at its inner end, said stamping having portions extending parallel to the planes of the flanges of said threaded receptacle contacts respectively to which said flanges are secured. 70 75

15   5. A plug receptacle comprising a plug portion and a receptacle portion, said plug portion comprising an insulating base and a threaded shell contact supported thereby, said receptacle portion comprising a one-piece insulating base supported by said plug portion, and having a plurality of open-ended cylindrical recesses therein, communicating
20 with each other, a plurality of threaded shell receptacle contacts, one for each of said cylindrical recesses, each insertable into its recess through the outer end thereof, anchorage means located at the junction of said cylindrical recesses, and means accessible for securing and releasing operation through the opening ends of said recesses for securing said threaded shell receptacle contacts to said anchorage means.

8. A plug receptacle comprising a plug portion and a receptacle portion, said plug portion comprising an insulating base and a threaded shell contact supported thereby, said receptacle portion comprising a one-piece insulating base supported by said plug portion, and having a plurality of open-ended cylindrical recesses therein, communicating with each other, a plurality of threaded shell receptacle contacts, one for each of said cylindrical recesses, each insertable into its recess through the outer end thereof, anchorage means located at the junction of said cylindrical recesses, and means accessible for securing and releasing operation through the opening ends of said recesses for securing said threaded shell receptacle contacts to said anchorage means, said anchorage means comprising a sheet metal stamping, and said securing means comprising screws threaded into said stamping, said stamping being electrically connected to the plug shell contact.

30 6. A plug receptacle comprising a plug portion and a receptacle portion, said plug portion comprising an insulating base and a threaded shell contact supported thereby, said receptacle portion comprising a one-piece insulating base supported by said plug portion, and having a plurality of open-ended cylindrical recesses therein, communicating with each other, a plurality of threaded shell receptacle contacts, one for each of said cylindrical recesses, each insertable into its recess through the outer end thereof, anchorage means located at the junction of said cylindrical recesses, and means accessible for securing and releasing operation through the opening ends of said recesses for securing said threaded shell receptacle contacts to said anchorage means, said anchorage means comprising a sheet metal stamping, and said securing means comprising screws threaded into said stamping.

9. A plug receptacle comprising a plug portion and a receptacle portion, said plug portion comprising an insulating base and a threaded shell contact supported thereby, said receptacle portion comprising a one-piece insulating base supported by said plug portion, and having a plurality of open-ended cylindrical recesses therein, communicating with each other, a plurality of threaded shell receptacle contacts, one for each of said cylindrical recesses, each insertable into its recess through the outer end thereof, anchorage means located at the junction of said cylindrical recesses, and means accessible for securing and releasing operation through the opening ends of said recesses for securing said threaded shell receptacle contacts to said anchorage means, said anchorage means comprising a sheet metal stamping, and said securing means comprising screws threaded into said stamping, said plug threaded shell contact having an inwardly extending flange at the outer end of the plug, and a screw, the head of which engages said flange and is threaded into said stamping. 105 110 115 120 125

7. A plug receptacle comprising a plug portion and a receptacle portion, said plug portion comprising an insulating base and a threaded shell contact supported thereby, said receptacle portion comprising a one-piece insulating base supported by said plug portion, and having a plurality of open-ended cylindrical recesses therein, communicating with each other, a plurality of threaded shell receptacle contacts, one for each of said cylindrical recesses, each insertable into its recess through the outer end thereof, anchorage means located at the junction of said cylindrical recesses, and

10. A plug switch receptacle comprising a plug portion, a receptacle portion, and a switch, said plug portion comprising an insulating base and a threaded shell con- 130

tact supported thereby, said receptacle portion comprising a one-piece insulating base supported by said plug portion, and having a plurality of open-ended cylindrical recesses therein communicating with each other, a plurality of threaded shell receptacle contacts, one for each of said cylindrical recesses, each insertable into its recess through the outer end thereof, said insulating base also having a switch recess therein in communication with said cylindrical recesses, anchorage means located at the junction of said recesses, and means accessible for securing and releasing operation through the opening ends of said recesses for securing said threaded shell receptacle contacts to said anchorage means.

11. A plug switch receptacle comprising a plug portion and a receptacle portion, said plug portion comprising an insulating base, and threaded shell and center contacts supported thereby, said receptacle portion comprising a one-piece insulating base supported by said plug portion and having a plurality of open-ended cylindrical recesses therein, communicating with each other, a plurality of threaded shell receptacle contacts, one for each of said cylindrical recesses, each insertable into its recess through the outer end thereof, anchorage means located at the junction of said cylindrical recesses, means accessible for securing and releasing operation through the opening ends of said recesses for securing said threaded shell receptacle contacts to said anchorage means, a center contact in each receptacle recess, switch contacts, one electrically connected with said plug center contact and one with one of said receptacle center contacts, and a switch arm for making and breaking the circuit with respect to said switch contacts.

12. A two-way plug receptacle comprising a plug portion and a receptacle portion, said receptacle portion comprising shell and center contacts and a casing therefor having two outlet openings extending at an angle

to each other for the insertion and removal of said shell contacts without rotation, and means accessible for operation through the open ends of said shell contacts whereby said shell contacts may be secured in place after they have been inserted in position through said openings.

13. A two-way plug receptacle comprising a plug portion and a receptacle portion, said receptacle portion comprising shell and center contacts and a casing therefor having two outlet openings extending at an angle to each other for the insertion and removal of said shell contacts without rotation, and means accessible for operation through the open ends of said shell contacts whereby said shell contacts may be secured in place after they have been inserted in position through said openings, said securing means comprising screws having their heads accessible for operation through the open ends of said shell contacts.

14. A two-way plug receptacle comprising a plug portion and a receptacle portion, said plug portion comprising an insulating base, a center contact mounted thereon and a threaded shell contact surrounding said insulating base, said receptacle portion comprising an insulating base, threaded shell and center contacts supported thereby, and means for securing said bases together and electrically connecting the plug center contact with the receptacle center contact comprising a screw extending axially through said bases, said receptacle portion having two outlet openings extending at an angle to each other for the insertion and removal of said shell contacts without rotation, and means accessible for securing and releasing operation through the open ends of said shell contacts whereby said shell contacts may be secured in place after they have been inserted in position through said openings.

In witness whereof, I have hereunto subscribed my name.

REUBEN B. BENJAMIN.
